UNITED STATES PATENT OFFICE.

NATHAN M. LOWER, OF PITTSBURGH, PENNSYLVANIA, ASSIGNOR TO LOCOMOTIVE STOKER COMPANY, A CORPORATION OF PENNSYLVANIA.

LOCOMOTIVE-STOKER.

1,363,333.

Specification of Letters Patent. Patented Dec. 28, 1920.

Application filed August 1, 1918. Serial No. 247,763.

To all whom it may concern:

Be it known that I, NATHAN M. LOWER, a citizen of the United States, and resident of Pittsburgh, county of Allegheny, and State of Pennsylvania, have invented certain new and useful Improvements in Locomotive-Stokers, of which the following is a specification and which are illustrated in the accompanying drawings, forming a part thereof.

The invention relates to stokers for locomotives, and has for its object the provision of means for relieving the pressure of the driving motor upon the fuel transfer-ring mechanism in the event of the device being stopped by clogging, in order that the clutch device connecting the power element with the transferring means may be released.

It consists of a device such as hereinafter described and as illustrated in the accompanying drawings, in which—

Figure 1 is a detail elevation of the back head of the locomotive fire-box, the fuel elevator and the driving engine, showing the application of the relief or regulating valve illustrated in Figs. 5 and 6;

Fig. 2 is a detail longitudinal section of the driving motor and its controlling and regulating valve, the motor being shown as on the power stroke;

Fig. 3 is a similar view, the motor being on the back stroke;

Fig. 4 is a detail section of the relief or regulating valve;

Fig. 5 is a similar view showing a modified form of construction, taken on the line 5—5 of Fig. 6;

Fig. 6 is a plan view of the valve casing shown in Fig. 5, some parts being shown in dotted lines;

Fig. 7 is a diagrammatic illustration of the application of the device when the form of valve of Figs. 2, 3 and 4 is employed;

Fig. 8 is a detail elevation, partly in section, of the back head of a locomotive and of the elevating mechanism of the stoker;

Fig. 9 is a sectional detail on the line 9—9 of Fig. 10, of the ratchet and pawl mechanism for driving one of the elevators; and

Figs. 10 and 11 are sectional views on the lines 10—10 and 11—11, respectively, of Fig. 9.

The back head of the locomotive fire-box

is represented at 10, and the hand firing door at 11. At 12 there is shown an elevating conduit of known type, the stoker usually comprising two such conduits associated with a transferring conduit (not shown) leading forwardly from the locomotive tender, the fuel transferring and elevating mechanism, in the form of screw conveyors as 75, being driven by a single motor, represented at 13, of the reciprocating type, the piston rod of the motor being shown at 14 and a rack-bar for connecting it with suitable pinions being indicated at 15.

The conveyor screw 75 comprises a hollow shaft sleeved upon a driving shaft 76, the lower end of which carries a bevel gear 77, meshing with the rack 15. This shaft projects through the upper end of the casing 12, upon which is mounted the head 16, carrying the ratchet and pawl mechanism, through which power is transmitted from the shaft 76 to the shaft of the screw. This ratchet and pawl mechanism comprises a ratchet wheel 78, keyed upon the shaft 76, and two pairs of pawls 79, 80, carried by the head 16 which is fixed to the shaft of the screw 75. The pawls of each pair face in opposite directions, and are urged into engagement with the ratchet wheel 78 by a spring 81 anchored to each. These pawls are adapted to engage the ratchet wheel alternatively, or both may be held out of engagement with it.

The pawls are controlled by a pawl lifter 82, in the form of a segmental plate depending between the pawls from a vertically movable cap 83. The pawl lifting plate 82 has an oblique slot 84, into which projects a pin 85 setting through the cover plate of the head 16. As the cap plate 83 is moved vertically the pawl lifter 82 is shifted laterally, thereby disengaging one of the pawls from the ratchet wheel and permitting the other to make contact with it.

The specific driving mechanism as shown and described is not claimed in this application.

Mechanical stokers are liable to become clogged and stopped either by congestion or by the presence of extraneous matter, such as scraps of metal, being accidentally intermixed with the fuel. When this occurs it becomes necessary to temporarily reverse the direction of the elevating means, and to this

end the clutch must be released. The stalling will occur on the power stroke of the motor, and as the clutch mechanism is then under pressure its manual disengagement is 5 difficult or impossible, and it becomes necessary to relieve this pressure, as by reversing the direction of the motor stroke, before the latter is completed.

The motor ordinarily used in connection 10 with the type of stoking mechanism illustrated is shown in Figs. 2 and 3, and comprises a cylinder 18 within which reciprocates a piston 19 provided with a rod 14. Steam is delivered to the motor at 20, and 15 exhausted therethrough at 21. The distributing valve 22 is of D form, and alternately connects ports 23 and 24 with the opposite ends of the cylinder and with the exhaust port 21. This valve is shifted by means of 20 a pair of differential pistons 25, 26, fixed upon its stem and reciprocating in suitable cylinders, steam entering at the port 20 being at all times effective upon the adjacent faces of the two pistons and normally holding 25 the valve 22 in the position shown in Fig. 2, representing the power stroke of the motor.

A controlling valve 27 of D form is mounted in a cylindrical valve chamber 28 30 formed in the head of the cylinder 18 and in axial alignment with the cylinder. The valve 27 is provided with a stem 29 extending into the cylinder 18 and loosely fitting within an axial aperture 30 in the piston 35 rod 14 and being provided at its inner end with a stud or cross-head 31. As the piston 19 completes its power stroke, moving in the direction indicated by the arrow in Fig. 2, the stem 29 is met by the bottom of the 40 aperture 30 and the valve 27 is thereby shifted to the position shown in Fig. 3. Upon the completion of the return stroke of the piston 19, the stud or cross-head 31 is engaged by a detent mounted upon the front 45 face of the piston and shown as taking the form of an apertured plate 32, and the valve 27 is shifted to the position of Fig. 2.

A port 33 connects the steam passage leading from the port 20 to the valve chamber 28, 50 and a steam passage 34 leads from this chamber to the end of the cylinder within which the piston 25 reciprocates. An exhaust passage 35 leads from this cylinder to the chamber 28 and is controlled by the valve 27, the 55 cavity of which connects it at suitable times with an exhaust passage 36 leading to the main exhaust passage of the motor. The valve 27 is provided with a rearwardly projecting stem 37, snugly fitting and reciprocating in a pocket in the casing within which this valve is housed, and a duct 38 connects this pocket with the cylinder 18.

With the parts in the position shown in Fig. 2, the passage 34 is closed by the valve 60 65 27, and the exhaust passage 35 is covered

by the rim of the piston 25. The passage 23 being connected with the exhaust port 21, pressure in the pocket which receives the stem 27 is relieved. Upon the shifting of the valve 27 to the position shown in Fig. 3, 70 pressure is applied to the outer face of the piston 25, and preponderates over the constant pressure upon the inner face thereof because of the counterbalancing action upon the inner face of the piston 26, forcing the 75 valve 22 downwardly to the position of Fig. 3 and thereby reversing the direction of the piston 19. A relief passage 39 leads from the rearward end of the cylinder, within which the piston 26 reciprocates, to the passage 80 leading to the exhaust port 21.

As thus far described the motor and its valve mechanism have been long in use, and the motor is under the control of the operator only by means of a throttle valve, not 85 shown, in the steam service pipe. If, therefore, the motor is stalled by an overload, necessarily occurring during the power stroke (Fig. 2), steam pressure continues to urge the piston to the left. The power being 90 maintained upon the clutch mechanism must be relieved in order to permit the operator to reverse the machine, and it therefore becomes important to provide an auxiliary valve for controlling the valve 22. Such a 95 valve is shown at 40 (Figs. 2, 3 and 4) as being housed and reciprocating in a casing 41 integral with the cylinder head. A passage 42 connects the chamber of the casing 41 with the passage leading from the inlet 100 port 20, and a passage 43 connects the interior of the casing with the upper end of the cylinder within which the piston 25 reciprocates. An exhaust port 44 is provided for the chamber of the casing 41. 105

The valve 40 is chambered, as shown at 45, and is provided with lateral ports 46, 47, both of which communicate with the chamber 45, these ports being spaced to register in alternation with the passages 110 42, 43, and with the passage 43 and port 44. When the valve is centrally positioned, as shown in Fig. 4, the several passages are all disconnected. If, with the valve 22 in the position shown in Fig. 2, it is desired to 115 reverse the movement of the piston 19, the valve 40 is shifted to the position shown in Fig. 3 to deliver steam above the piston 25, forcing it downward and opening the port 23 to live steam and connecting the port 24 120 to the exhaust port 21. Thereupon the piston 19 will be moved to the right, thereby relieving the pressure upon the clutch mechanism. While the valve 40 remains in the position shown in Fig. 3, the motor will be 125 inactive, either because of continued pressure through the port 23 or because of the partial return of the piston 25 due to the relief of pressure above it through the passage 35. By shifting the valve 40 to the 130

position of Fig. 2, steam is exhausted from above the piston 25 through the passage 43 and port 44, again opening the passage 24 to live steam, and the normal operation of 5 the motor is secured by returning the valve 40 to its middle position.

When, as in the construction illustrated in Figs. 2, 3 and 4, the valve casing 41 is formed in the head of the cylinder 18, the 10 valve 40 is preferably controlled by means of a hand lever 48, fixed upon a rock shaft 49, journaled in brackets 50, 51, fixed to the back head of the fire-box above the fire door 11, and provided at its opposite ends with a 15 crank arm 52, a link 53 connecting this arm with a lever 54 pivoted on a suitable support and properly connected with the stem 55 of the valve.

If desired the controlling valve may be 20 located on the back head of the fire-box above the door 11 and connected with the passage 43 by a pipe 56, as illustrated in Fig. 1.

When this arrangement is employed the 25 controlling valve and its casing may take the form illustrated in Figs. 1, 5 and 6. The casing 57 is provided with a steam port 58, with which a pipe 59 is connected, a port 60 with which the pipe 56 is connected, 30 and an exhaust port 61 to which a pipe may be attached leading to any suitable point of discharge. Within the casing 57 there is housed a reciprocating cylindrical and tubular valve 62, having an external annular 35 cavity 63 of sufficient width to connect the ports 58, 60. When the valve is in the position shown in Fig. 5, the port 60 is closed, and when it is moved to the left this port is connected with the exhaust port 61.

40 The valve is controlled by means of a handle 64, fixed upon a shaft 65 projecting into the casing 57, and provided with a crank arm 66 pivotally attached to the stem 67 of the valve. A quadrant 68, attached to the 45 hub of the handle 64, is provided with a series of recesses 69, 70, 71, for coöperating with a spring-advanced detent 72 housed within a suitable pocket formed in the valve casing, whereby the valve is releasably held 50 in any of its three positions. By reason of its tubular and cylindrical form the valve 62 is completely balanced.

The result secured by the two forms of construction are identical, and the valve 55 may be further modified without departing from the scope of the invention.

I claim as my invention—

1. In a locomotive stoker, the combination with fuel-advancing means, a reciprocating driving motor and clutch mechanism connecting such elements, automatic valve mechanism for controlling the motor, and a supplemental manually controlled valve for reversing the direction of movement of the 65 motor piston during its stroke.

2. In a locomotive stoker, the combination with fuel-advancing means, a reciprocating driving motor and clutch mechanism connecting such elements, automatic valve mechanism for controlling the motor, and manually controlled means for relieving the 70 pressure of the motor upon the clutch mechanism.

3. In a locomotive stoker, the combination with fuel-advancing means, a reciprocating 75 driving motor and clutch mechanism connecting such elements, a fluid actuated distributing valve for the motor, a controlling valve actuated by the motor piston for shifting the distributing valve, and a manually controlled auxiliary valve for shifting the 80 distributing valve independently of the controlling valve.

4. In a locomotive stoker, the combination with fuel-advancing means, a reciprocating 85 driving motor and clutch mechanism connecting such elements, a fluid actuated distributing valve for the motor, a controlling valve actuated by the motor piston for shifting the distributing valve, and means 90 for shifting the distributing valve independently of the action of the motor piston on the controlling valve.

5. In a locomotive stoker, the combination with fuel-advancing means, a reciprocating 95 driving motor and clutch mechanism connecting such elements, a distributing valve for the motor, a reciprocating fluid-actuated motor for shifting the valve, a controlling valve for the shifting motor actuated by the 100 movements of the piston of the first-named motor, a supplemental passage for a fluid under pressure leading to the shifting motor, and a manually actuated valve for controlling such passage.

6. In a locomotive stoker, the combination with fuel-advancing means, a reciprocating driving motor and clutch mechanism connecting such elements, a valve casing, a service passage leading to the casing, passages connecting the casing to the opposite ends of the motor cylinder and to the exhaust, a valve controlling such three last-named passages, differential pistons reciprocable in the casing and being located on opposite sides of the adit of the service passage and being connected with the named valve, service and exhaust passages leading to the casing and effective upon the outer face of the larger of the differential pistons, 115 a valve actuated by the motor piston for controlling the last-named two passages, an additional service passage entering the casing and opening thereto beyond the outer face of the larger of the differential pistons, 120 and a manually-actuated valve for controlling the last-named passage.

7. In a locomotive stoker, the combination with fuel-advancing means, a reciprocating driving motor and clutch mechanism con- 130

necting such elements, a valve casing, a service passage leading to the casing, passages connecting the casing to the opposite ends of the motor cylinder and to the exhaust, a 5 valve controlling such three last-named passages, differential pistons reciprocable in the casing and being located on opposite sides of the adit of the service passage and being connected with the named valve, service and 10 exhaust passages leading to the casing and effective upon the outer face of the larger of the differential pistons, a valve actuated by the motor piston for controlling the last-named two passages, an additional passage 15 entering the casing and opening thereto beyond the outer face of the larger of the differential pistons, and a manually actuated valve for connecting the last-named passage in alternation with a source of pressure and 20 with an exhaust port.

8. In a locomotive stoker, in combination, fuel-advancing means, a reciprocating motor, reversible pawl and ratchet mechanism connecting the motor with the advancing 25 means, manually controlled means for shifting the pawls, and manually controlled means for reversing the direction of move-

ment of the motor piston during its power stroke.

9. In a locomotive stoker, in combination, 30 means for advancing fuel, ratchet and pawl mechanism for driving such means, power means for actuating such mechanism, and means for relieving pressure upon such mechanism during its advance movement, 35 such action leaving the mechanism in operative condition.

10. In a locomotive stoker, in combination, means for advancing fuel, ratchet and pawl mechanism for driving such means, 40 power means for actuating such mechanism, and means for reversing the movement of the pawls comprised in such mechanism before the completion of the advance movement thereof.

11. In a locomotive stoker, in combination, means for advancing fuel, mechanism for driving such means, power means for actuating such means, and mechanism for relieving pressure upon such mechanism 50 during its advance movement, the action of the said last-named means leaving said mechanism in operative condition.

NATHAN M. LOWER.

Corrections in Letters Patent No. 1,363,333.

It is hereby certified that in Letters Patent No. 1,363,333, granted December 28, 1920, upon the application of Nathan M. Lower, of Pittsburgh, Pennsylvania, for an improvement in "Locomotive-Stokers," an error appears in the printed specification requiring correction as follows: Page 4, line 49, claim 11, for the word "means" read *mechanism* and for the word "mechanism" read *means*; and that the said Letters Patent should be read with these corrections therein that the same may conform to the record of the case in the Patent Office.

Signed and sealed this 25th day of January, A. D., 1921.
